INVENTOR

Thos. Boyd
By his attorney
James Johnston.

United States Patent Office.

THOMAS BOYD, OF ALLEGHENY CITY, PENNSYLVANIA.

Letters Patent No. 78,859, dated June 16, 1868.

IMPROVEMENT IN HEATING BUILDINGS.

The Schedule referred to in these Letters Patent and making part of the same.

TO ALL WHOM IT MAY CONCERN:

Be it known that I, THOMAS BOYD, of the city and county of Allegheny, in the State of Pennsylvania, have invented a new and useful Improvement for Heating Buildings; and I do hereby declare that the following is a full and exact description thereof, reference being had to the accompanying drawings, and to the letters and figures of reference marked thereon.

The nature of my invention consists in surrounding the ordinary fire-chamber and its smoke-flue with an air-chamber, which terminates in the fireplace of an upper room, said smoke-flue passing up into and out of the fireplace of said upper chamber, into a side-flue, the whole being constructed, arranged, and operating in the manner hereinafter described.

To enable others skilled in the art to make and use my invention, I will proceed to describe its construction and operation.

In the accompanying drawings, which form part of my specification—

Figure 1 is a transverse section of an ordinary building, and represents a longitudinal section of the chimney and its fireplaces, provided with my improvement.

Figure 2 is a longitudinal section of the chimney, showing a side view of it, and provided with my improvement.

In the drawings, A represents the basement, B the first story, C the second story, and D the upper story or attic of the building. x represents the chimney-walls.

In the first story, B, is a fireplace, n, which consists of an ordinary grate, surrounded with a brick or metallic wall, marked 5, which is surrounded by an air-chamber, marked 3, and connected with a flue, 2, which terminates in the fireplace m of the second story. The fireplace n is provided with a sheet-iron smoke-flue, which passes up in the flue 2, into the fireplace m, and from it into a side-flue marked 1. The fireplace m, in the second story, is provided with a flue, marked 2', in which is placed a valve, o. It will readily be observed that the flue 2' may be provided with a valve, and an opening leading into each room above the second story C, so that the heat may be thrown into any room above the first story B by a simple manipulation of the valves.

The skillful mechanic will readily understand the construction and arrangement of my improvement from the foregoing description, and by reference to the accompanying drawings; therefore I will at once proceed to describe its operation, which is as follows:

Fire being made in the fireplace n, the smoke, dust, and other refuse of combustion, will pass up through the flue 4 into the flue marked 1, and up through it and out at the chimney-top. Cold air is admitted into the air-chamber 3 through the opening 6. The air thus admitted becomes heated and rarefied, and passes up through the flue 2 into the fireplace m, from which it enters the room of the second story C. The temperature of the room of the second story may be regulated to any desired degree through the medium of the valve o. It will be observed that the air, after it leaves the chamber 3, is subjected to the heat radiating from the iron flue 4, until it leaves the fireplace m of the second story.

From the foregoing description, and by reference to the accompanying drawings, it will readily be seen that the flues 1, 2, and 2', are straight, and that the smoke from the flue 4, and the dust from the ash-chamber, pass into the side-flue 1, and that flue 4 can be removed and repaired readily, without the necessity of going on the roof of the house, or any disarrangement of the flues 1, 2, and 2'. And it will also be observed that the construction of the chimney and its flues is greatly simplified, and more secure from the danger of fire than the flues of the ordinary chimney, for the draught is more direct and straight, and that flues are not so liable to become choked and clogged with soot, dust, and other refuse of combustion.

The advantages of my improvement are—

First, the room or rooms above the first story can be heated when there is fire in the fireplace of the first story, without cost.

Second, the trouble of carrying fuel up stairs, and the ashes and other refuse of combustion down stairs, is avoided.

Third, the dirt and dust consequent upon having a fire in the upper rooms, are avoided, hence the housewife is saved much trouble and labor.

The ash-chamber 6' of the fireplace *n* should be connected with the flue marked 1, for the purpose of carrying off the dust caused by the stirring up the fire and the rattling down of ashes. This may be accomplished by making a flue or opening to lead from the ash-chamber 6 into the flue 1, as indicated by the dotted lines 7.

I wish it clearly understood that I do not claim a stove placed in an ordinary fireplace, nor do I claim placing a pipe or pipes for heating air in the flues of an ordinary fireplace; neither do I claim broadly an air-chamber around a fireplace, stove, or other heating-device, and connecting therewith a pipe or pipes, for conducting heated air into upper rooms of buildings; but having thus described the nature, construction, operation, and advantages of my invention,

What I claim as of my invention, is—

The arrangement of the flues 1, 2, 2', and 4, fireplaces *m* and *n*, air-chamber 3, and valve *o*, the whole being constructed, arranged, and operating as herein described, and for the purpose set forth.

THOS. BOYD.

Witnesses:

JAMES J. JOHNSTON,

A. C. JOHNSTON.
